UNITED STATES PATENT OFFICE.

REGINALD G. STANDERWICK, OF MARBLEHEAD, MASSACHUSETTS, ASSIGNOR TO GENERAL ELECTRIC COMPANY, A CORPORATION OF NEW YORK.

REGULATING MECHANISM FOR ELASTIC FLUID TURBINES.

Application filed April 23, 1926. Serial No. 104,234.

The present invention relates to regulating mechanism for elastic fluid turbines and has for its object to provide an improved structure and arrangement in a mechanism of this character.

The invention as to certain of its features may be embodied in regulating mechanisms for various types of turbines, such as, for example, mixed pressure turbines, extraction turbines, turbo-compressor sets, and the like. As to certain other features, it is especially adapted to extraction turbines, and I have accordingly specifically illustrated the invention applied to an extraction machine.

For a consideration of what I believe to be novel and my invention, attention is directed to the accompanying description and the claims appended thereto.

In the drawing, Fig. 1 is a diagrammatic view of a regulating mechanism embodying my invention applied to an extraction turbine; Fig. 2 is a side elevation of a turbine and regulating mechanism; Fig. 3 is an end view thereof; and Figs. 4, 5 and 6 are detail sectional views of certain parts on a larger scale than that of Fig. 1.

Referring to the drawing, 1 indicates an elastic fluid turbine, 2 being the casing or shell of the turbine and 3 the shaft. Elastic fluid is supplied to the high pressure end of the turbine through a conduit 4, and exhausts through a housing 5 to a suitable condenser (not shown). The flow of elastic fluid from conduit 4 to the first stage nozzles (not shown) is controlled by a primary valve 6 and a group or series of secondary valves 7. Primary valve 6 controls the flow of elastic fluid through a passage 8 to one group of first stage nozzles and secondary valves 7 control the flow of elastic fluid from an elastic fluid chest 9 to another group of first stage nozzles. Valves 6 and 7 are biased toward closed positions by springs 10 and are opened against the biasing action of such springs by a series of pivoted lever arms 11 provided with rollers 12 at their free ends which engage cams 13 on a cam shaft 14. The arrangement is such that when cam shaft 14 turns in one direction valve 6 is first opened after which valves 7 are successively opened. When cam shaft 14 turns in the other direction, valves 7 are successively closed after which valve 6 is closed.

The general arrangement of the levers for

operating each of the valves 6 and 7 is the same. An outline of the connections for one of the valves 7 is shown in section in Fig. 1. The stem 15 of the valve projects through a wall 16 which forms a part of a supporting bracket 17 on which lever 13 is pivoted, and at its upper end extends through an opening in a web 18, which forms a part of lever 13. On the upper end of stem 15 is arranged a collar 19, which rests on rounded projections 20 on web 18. Spring 10 is arranged between a collar 21 on a stem 15 and the under surface of wall 16. With this arrangement it will be seen that when the right hand end of lever 13 is raised, valve 7 will be opened against the biasing action of spring 10. On one end of cam shaft 14 is a pinion 22 with which engages teeth on a rack 23. Rack 23 is fastened on the upper end of a stem 24, which at its lower end is connected to a piston 25 which moves in a cylinder 26. Piston 25 is biased towards an annular stop 27 in the lower end of cylinder 26 by a suitable spring means 28. When piston 25 moves upward in cylinder 26 it turns cam shaft 14 in a direction to open valves 6 and 7 while when it moves downward it turns shaft 14 in a direction to close valves 6 and 7.

The valve gear and operating means therefor so far described is shown only by way of example and forms no part of my present invention. It is a known type and is to be taken as typical of any suitable valve gear adapted to regulate the admission of elastic fluid to a turbine. For this reason, the structure is shown only in outline, complete details of the arrangement being omitted.

The elastic fluid turbine illustrated is an extraction turbine, that is, a machine where-in elastic fluid is taken from an intermediate stage for industrial or other purposes. In Fig. 1 the section of the turbine is taken through the extraction stage conduit 29, being the conduit through which elastic fluid is extracted from the turbine. The flow of elastic fluid from the extraction stage to the next lower stage is controlled by a ring valve or overflow valve 30, the purpose of this valve being to maintain constant the pressure in the extraction stage.

The use of a ring valve or overflow valve for this purpose is well understood in this

- art, and the same is accordingly illustrated only in outline. A mechanism of this type is well illustrated in the patent to Fred E. Norton, 1,091,078, patented March 24, 1914.
- 5 Ring valve 30 is moved by means of teeth on a rack 31, which engage similar teeth on a gear segment 32 attached to ring valve 30. Rack 31 is connected by a rod 33 to a piston 34, which moves in a cylinder 35. 10 The admission of actuating fluid to cylinder 35 is controlled by a pilot valve structure 36. Piston 34, cylinder 35 and pilot valve 36 form a usual type of fluid-actuated motor to be used in positioning ring valve 30. The 15 stem of pilot valve 36 is pivotally connected to a floating lever 37. The lower end of lever 37 is pivoted to an arm 38, which in turn is pivoted on a fixed bracket 39. The free end of arm 38 is pivotally connected 20 to an extension 40 of rod 33. The upper end of floating lever 37 is pivotally connected to one end of a bell crank lever 41, which is fulcrumed on a bracket 42. Movement of bell crank lever 41 serves to move pilot 25 valve 36 and thus control the admission of actuating fluid to cylinder 35 in the well understood manner. Lever arm 38 and extension 40 form a usual arrangement of follow-up connection for the fluid-actuated 30 motor. The arrangement of the fluid-actuated motor for operating ring valve 30 is shown only diagrammatically and by way of example, such arrangements being well known in this art.
- 35 In the operation of an extraction turbine, it is desired to maintain the pressure in the extraction stage substantially constant, the pressure being controlled by the ring valve or other valve means which regulates the 40 flow of elastic fluid from the extraction stage to the next lower stage, as is well understood. To accomplish this, it is desirable to regulate the admission of elastic fluid to the turbine and the flow of elastic fluid from the extraction stage in accordance with both the load on the turbine and the pressure in the extraction stage. When the load on the turbine increases or decreases the valve means regulating the flow of elastic fluid to the turbine and 45 the valve means regulating the flow of elastic fluid from the extraction stage to the next lower stage should be operated both in the same direction or sense, that is, opened and closed together. On the other hand, when the pressure in the extraction stage increases, then it is desirable to open further the valve means controlling the flow of elastic fluid from the extraction stage to the next lower stage and close further the valve means 50 regulating the flow of elastic fluid to the turbine, while when the extraction pressure decreases, it is desirable to close somewhat the valve means controlling the flow of elastic fluid from the extraction stage to the next lower stage and open somewhat the valve 55 means regulating the admission of elastic fluid to the turbine. Thus it will be seen that with changes in load the admission valve mechanism and the overflow valve mechanism are operated in the same direction or sense while with changes in the extraction pressure they are operated in opposite directions or in the opposite sense. My improved regulating means, whereby the foregoing result is accomplished will now be 60 described.
- Mounted on the bearing pedestal 43 at the high pressure end of the turbine are two control mechanisms A and B. The correct relative arrangements of these two mechanisms is shown in Figs. 2 and 3. In Fig. 1 they are illustrated diagrammatically one in advance of the other, the bearing pedestal 43 being shown twice. Also in Fig. 1, the section through the turbine and the high pressure valve gear are not shown in correct relative relation to each other or to the diagrammatic showing of bearing pedestal 43, but are arranged in positions so as to clearly illustrate the principle of the invention.
- Referring particularly to Figs. 1 and 5, the mechanism A comprises a vertical shaft 44, which is driven by a worm wheel 45, carried by a shaft 45^a, which in turn is connected to the turbine shaft. On the upper end of shaft 44 is a speed governor comprising weight arms 46 and a spring 47, the arrangement being such that as the speed increases and decreases, the weight arms move outward and inward against the action of spring 47 by centrifugal force. The governor is connected by a yielding connection 48 to a pilot valve member 49. Pilot valve member 49 comprises a tubular sleeve and rotates continuously with the governor. At the same time when weights 46 move, valve member 49 is moved up and down. The governing mechanism is enclosed in a housing 50 on which is mounted a pilot valve casing 51. Inside pilot valve casing 51 is a restoring bushing 52, provided with ports 53 which serve to connect the interior of bushing 52 to an annular chamber 54 formed between casing 51 and bushing 52. Connected to annular chamber 54 is a pipe 55 through which fluid flows to the chamber. The flow of fluid from the chamber through passages 53 is controlled by the upper end of pilot valve member 49. Bushing 52 is carried on the lower end of a threaded rod 56. By turning rod 56 and bushing 52 relatively to each other the position of bushing 52 may be adjusted relatively to pilot valve casing 51. This adjustment may be effected either manually by means of a handwheel 57, or by means of an electric motor 58. This adjusting arrangement is indicated only diagrammatically as it forms no part of the present invention. It is indicated as being of the type disclosed and claimed in

the patent to Paul H. Scott, No. 1,583,610, granted May 4, 1926.

The upper end of rod 56 is connected to a lever 59. One end of lever 59 is fulcrumed on the upper end of a rod 60, the arrangement being such that the fulcrum point may be adjusted back and forth, as is indicated by the holes 61. The other end of lever 59 is connected by a rod 62 to the lower end of a corrugated bellows 63, arranged in a casing 64. Bellows 63 and casing 64 are attached to the underside of a bracket arm 65 provided with a comparatively large central opening 66 which connects the interior of the bellows to atmosphere. The exterior of bellows 63 is subjected to the pressure in casing 64. Inside bellows 63 is a sleeve 67 which forms a stop to limit the movement of bellows 63 in an upward direction. On rod 62 is a collar 68 against which bears one end of a spring 69, the other end bearing against a block 69^a fixed to sleeve 67. Spring 69 thus acts in a direction to contract bellows 63.

Referring now to Figs. 1 and 4, mechanism B comprises a pilot valve casing 70 provided with a stationary bushing 71 which defines with casing 70 an annular chamber 72. In bushing 71 are a series of ports 73 which connect chamber 72 to the interior of the bushing. Inside bushing 71 is a tubular pilot valve member 74 to the lower end of which is connected a rod 75. Pilot valve member 74 serves to cover and uncover the ports 73. The upper end of rod 75 is pivotally connected to a floating lever 76. One end of floating lever 76 is connected by a stem 77 to the lower end of a corrugated bellows 78. Bellows 78 is located in a fluid-tight casing 79. The interior of bellows 78 is open to atmosphere and the exterior is subjected to the pressure in casing 79. 80 is a sleeve which forms a stop to limit upward movement or collapsing movement of the bellows. The other end of floating lever 76 is connected by a link 81 to one arm 82 of a bell crank lever. The other arm 83 of the bell crank lever is connected by a rod 84 to an eccentric 85 (see Fig. 3) on shaft 14, the rod being provided with an eccentric strap 86 which surrounds the eccentric.

Arranged adjacent to the turbine at one side of it or at any other convenient location, is a unitary control mechanism C. It comprises a pedestal 90 (Figs. 2 and 3), having a bottom wall 91 and a top wall 92. Mounted on the bottom wall 91 is a pressure-responsive mechanism D, and mounted on top wall 92 is a mechanism E. The detail structure of mechanisms D and E is shown in Fig. 1. Mechanism E is enclosed by a cover 93.

Referring to Fig. 1, the pressure responsive mechanism D comprises a fluid-tight casing 94 in which is arranged a corrugated

bellows 95. The interior of bellows 95 is open to atmosphere while the exterior is subjected to the pressure in casing 94. Engaging the lower head 96 of bellows 95 is a rod 97. On rod 97 is a spring plate 98 to which is attached one end of a spring 99, the other end of the spring being attached to a spring plug 100 on the top of casing 94. Spring 99 is a tension spring and serves to oppose the collapsing of bellows 95. The rod 97 extends upward to the mechanism E and its upper end engages the under side of a lever 101. Lever 101 is pivoted on the upper end of a bracket 102. One end of lever 101 is connected by a link 103 to a pair of arms 104. The outer ends of arm 104 are connected to a pair of arms 105 which in turn are pivoted to each other and to a link 106 which serves to connect them to a stationary support 107. The points at which arms 104 and 105 are connected together are joined by a spring 108 so that when the left hand end of lever 101 moves up and down it extends and compresses the spring. The spring thus serves to oppose upward movement of the lever 101. The purpose of spring 108 is to modify the characteristics of bellows 95 and spring 99. The details of its construction and method of operation are not set forth herein as they form the subject matter of my application, Serial No. 104,235, filed of even date herewith. For the purpose of the present invention, it is necessary only to state that bellows 95, spring 99 and spring 108 all operate together to provide a pressure responsive construction capable of being moved to effect movement of lever 101 by comparatively small changes in the pressure applied to bellows 95, and, at the same time, a construction wherein equal changes in the pressure to which bellows 95 is subjected effect substantially equal movements of the bellows. The construction comprising spring 108 forms what I term an inverted elastic connection. It has a straight line characteristic and serves to modify the characteristics of the simple elastic connection comprising bellows 95 and spring 99 to the desired extent.

The other end of the lever 101 is connected by a link 109 to arm 110 of a three-arm lever, the other arms of which are indicated at 111 and 112. Arms 111 and 112 are integral with each other and are connected to arm 110 by a bolt 112^a, the bolt passing through an elongated slot 112^b in arms 111 and 112. By this arrangement the relative lengths of arms 111 and 112 can be adjusted. The three-arm lever is pivotally mounted by an extension of bolt 112^a on one end of a lever 113 pivoted at 114 on bracket 102. The other end of lever 113 is connected by a rod 115 to a bellows structure comprising an inner bellows 116 and an outer

- bellows 117, suitably connected together at their upper and lower ends and mounted in a fluid-tight casing 118. The annular chamber between bellows 116 and 117 is connected by a pipe 119 to fluid-tight casing 64 of the mechanism A and the interior of casing 118 is connected to pipe 55. 119^a is a spring which acts in a direction to oppose collapsing of the bellows structure.
- 10 The end of lever arm 111 is connected by a rod 120 to a corrugated bellows 121 contained in the fluid-tight casing 122. The interior of bellows 121 is open to atmosphere while the outside of it is subjected to the pressure in casing 122. Casing 122 is connected by a pipe 123 to a fluid-tight casing 124 in which is located a corrugated bellows 125 connected by a rod 126 to one arm of bell crank lever 41. 127 is a sleeve which 15 forms a stop to limit the collapsing movement of bellows 125 and 128 is a spring which opposes collapsing movement of the bellows. Inside of bellows 121 is a stop sleeve 129.
- 15 Arm 112 of the three-arm lever is connected by a rod 130 to a corrugated bellows 131 located in a fluid-tight casing 132. The interior of bellows 131 is open to atmosphere while the exterior is subjected to the 20 pressure in casing 132. Inside bellows 131 is a stop sleeve 133. Casing 132 is connected by a pipe 134 to the interior of fluid-tight casing 79 which forms a part of the mechanism B.
- 25 The space between bellows 116 and 117, pipe 119, and casing 64; casing 122, pipe 123, and casing 124; and casing 132, pipe 134, and casing 79, are in each instance filled 30 completely with a suitable liquid, the arrangements forming in each case an hydraulic means for transmitting movement from one corrugated bellows to the other.
- 30 The lower end of vertical shaft 44 drives a suitable pump 135 located in an oil tank 136. The suction conduit for pump 135 is indicated at 137 and the discharge pipe is indicated at 138. Connected to discharge pipe 138 is a branch pipe 139 which leads to a pressure relief valve 140 in tank 136. Pressure relief valve 140 is set so as to maintain 35 in pipe 138 a substantially constant desired pressure. Pipe 138 supplies oil through an orifice 141 in a plate 142 to a pipe 143, and through an orifice 144 in a plate 145 to pipe 55. Pipe 143 is connected to cylinder 26 beneath piston 25. Extending from pipe 143 is a branch pipe 146 which connects with annular chamber 72 of mechanism B. Since the pressure in pipe 138 is substantially constant, substantially a constant quantity of oil is discharged continuously through orifices 141 and 144 to pipes 143 and 55. 147 indicates a drain pipe for conveying oil back to tank 136. Extraction conduit 29 is connected to casing 94 by a pipe 148, whereby 40 the corrugated bellows 95 is subjected at all times to the pressure of the extraction elastic fluid.
- 40 The operation is as follows: Assume that the turbine is running under load at the desired speed, that elastic fluid is being extracted through conduit 29, and that ring valve 30 is in a position such that the desired pressure obtains in the extraction conduit. Under these circumstances, pump 135 will 45 be supplying oil continuously to orifices 141 and 144, and a definite quantity of oil will be flowing through them to pipes 143 and 55. The oil supplied to pipe 143 flows through branch pipe 146 to annular chamber 72 in 50 mechanism B, and from thence it flows over the end of pilot valve member 74 and down through it back to oil tank 136. Pilot valve member 74 is located in a position relatively to annular chamber 73 such that a pressure 55 is built up in pipes 143 and 146, and hence under piston 25, which pressure holds the piston in a position to maintain valves 6 and 7 open to an extent such that sufficient elastic fluid is admitted to the turbine to carry 60 the load and supply the necessary steam for extraction purposes. The oil supplied through orifice 144 to pipe 55 flows to annular chamber 54 of mechanism A and can escape therefrom through ports 53 and down 65 through pilot valve member 49 back to oil tank 136. With the desired turbine speed obtaining, pilot valve member 49 is positioned to maintain a pressure in pipe 55, and hence in fluid-tight casing 118, such 70 that lever 113 is held in a certain predetermined position due to the action of the oil pressure on the bellows structure comprising bellows 116 and 117.
- 70 If now for any reason, for example, due to decrease in load, the speed of the turbine increases, then the weight arms 46 and 47 of the speed governor fly outward, lowering somewhat pilot valve member 49 relatively to restoring bushing 52. This uncovers further the ports 53 permitting oil to escape more rapidly from pipe 55. This lowers somewhat the pressure in pipe 55 with the result that spring 119^a distends the bellows structure comprising bellows 116 and 117, 75 thus turning lever 113 in an anticlockwise direction on its pivot 114. This lowers the left-hand end of lever 113 and pulls down three-arm lever comprising arms 110, 111, and 112, as a unit. When the three-arm 80 lever moves downward both corrugated bellows 121 and 131 are collapsed somewhat. The collapsing of bellows 121 draws fluid from casing 124 with the result that corrugated bellows 125 is distended somewhat. The distension of bellows 125 operates 85 therough rod 126 to turn bell crank lever 41 on its pivot on bracket 42, and to move the upper end of vertical lever 37 toward the left. This movement of lever 37 moves pilot 90

valve 36 toward the left and effects a movement of piston 24 to the right and in a direction to close somewhat the ring valve 30, thereby decreasing the amount of elastic fluid which can flow by the ring valve to the subsequent turbine stages. When piston 24 moves to the right it restores pilot valve 36 through the follow up connection 38 in the well understood manner. At the same time, the collapsing of corrugated bellows 131 serves to draw fluid from casing 79 of mechanism B, thereby distending corrugated bellows 78. This lowers the right-hand end of floating lever 76, thereby lowering pilot valve member 74 and uncovering further ports 73. This permits oil to escape more rapidly from pipe 146 thereby lowering the pressure under piston 25. Spring 28 thereupon forces piston 25 downward in a direction to close somewhat the valve mechanism controlling the admission of elastic fluid to the turbine. When piston 25 moves downward it turns cam shaft 14 with the result that eccentric 85 moves lever 84 in a direction to turn bell crank lever arm 82 clockwise, which serves to raise pilot valve sleeve 74, thus moving it back toward its previous position, and preventing overtravel of piston 25. When corrugated bellows structure 116 and 117 moves upward it serves to draw liquid from casing 64, thus decreasing the pressure in the casing and effecting a distending movement of bellows 63. This movement of the bellows lowers the right-hand end of lever 59, thereby moving restoring bushing 52 downward to prevent overtravel of the governing mechanism.

In case of a decrease in speed of the turbine due to increase in load, for example, then weights 46 and 47 move inward somewhat under the action of the governing spring thereby raising pilot valve member 49 and increasing the pressure in pipe 55. An action similar to that just described except in the opposite direction then takes place, the ring valve 30 and the valve mechanism for the turbine being both given an opening movement.

If the pressure in extraction conduit 29 decreases, which indicates an increase in the demand for extraction elastic fluid, the pressure in casing 94 decreases, whereupon bellows 95 is distended. This causes lever 101 to turn on its pivot on bracket 102 in an anticlockwise direction. As a result link 109 and lever arm 110 are moved toward the left thereby lowering the outer end of lever 111 and raising the outer end of lever 112.

As will be clear from the explanation given above, a lowering of the right hand end of lever 111 results in effecting a movement of ring valve 30 in a direction to close it somewhat while the raising of the outer end of lever 112 results in an opening movement of the valve mechanism controlling

the admission of elastic fluid to the turbine. As a result the amount of elastic fluid supplied to the turbine is increased while the amount which can flow past the ring valve 30 to the subsequent stages of the turbine is decreased. Thus the supply of elastic fluid for extraction purposes is increased and the pressure brought back to normal. If the pressure in extraction conduit 29 increases, which indicates a decrease in the demand for extraction elastic fluid, then the increased pressure acting on corrugated bellows 95 serves to collapse it somewhat with the result that lever 110 is moved toward the right, thus raising the outer end of lever 111, and lowering the outer end of lever 112. As a result, the amount of elastic fluid admitted to the turbine is decreased, while the ring valve is opened somewhat, permitting more elastic fluid to flow to the subsequent turbine stages. This serves to decrease the supply of elastic fluid available for extraction purposes and brings the pressure back to normal.

By adjusting lever arms 111 and 112 relative to lever arm 110, this being accomplished by reason of slot 112^b, the relative relation between the operation of ring valve 30 and the valve means comprising valves 6 and 7 when the three-arm lever is turned, can be changed. This is a thing of considerable importance in the practical use of my invention. It will be understood that when lever arms 111 and 112 are moved, the structures comprising casings 122 and 132 are adjusted along with them.

It will be seen that the two bellows devices 121 and 131 form movable devices through which movement of the pilot valve 36 for ring valve 30 and pilot valve 74 for valve means 6 and 7 is effected, and that bellows devices 95 and 116, 117 form operating devices for effecting movements of said movable devices. Also, it will be seen that the operating device comprising bellows 95 responds to one operating condition of the turbine (in the present instance, the extraction pressure), and that the operating device comprising bellows 116, 117 responds to another operating condition of the turbine (in the present instance, the speed of the turbine). Furthermore, it will be understood that while I have illustrated the various devices as being in the form of bellows (this being the arrangement I now prefer), my invention is by no means limited thereto, since any other equivalent type of device may be used.

With the above-described arrangement it will be seen that the major portion of the control apparatus is carried by the pedestal 90. This forms a unitary control mechanism, which may be placed at any point adjacent to or remote from the turbine, the only connections between it and the mechanism on the turbine being the piping con-

- necting them. This greatly simplifies the mechanism to be mounted on the turbine and avoids the necessity of mounting a large number of levers and rods on the turbine.
- 5 This is of advantage in that it renders the parts more accessible and does away with the possibility of binding of the levers which may be caused for example by uneven expansion of the turbine parts. A control
- 10 mechanism for a turbine is a comparatively exact piece of apparatus and any binding of the operating parts may cause faulty operation. The arrangement also has the advantages of being compact, of being capable of manufacture at a low cost, and of being reliable in operation.
- 15

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

25 25 What I claim as new and desire to secure by Letters Patent of the United States is:

1. The combination with an elastic fluid turbine, of valve means controlling the flow of elastic fluid to the turbine, a fluid-actuated motor for moving the valve means, a pilot valve for controlling the fluid pressure supplied to said motor, a unitary structure comprising a movable device and two separate operating devices either of which is adapted to effect movement of said movable device, means responsive to the speed of the turbine for effecting movement of one of said operating devices, means responsive to another operating condition of the turbine for effecting movement of the other of said operating devices, and hydraulic means for transmitting movement from the movable device to said pilot valve.

2. The combination with an elastic fluid turbine, of valve means controlling the flow of elastic fluid to the turbine, a fluid-actuated motor for moving the valve means, a pilot valve for controlling the fluid pressure supplied to said motor, a unitary structure comprising a movable device and two separate operating devices either of which is adapted to effect movement of said movable device, means responsive to the speed of the turbine for effecting movement of one of said operating devices, means responsive to another operating condition of the turbine for effecting movement of the other of said operating devices, hydraulic means for transmitting movement from the movable device to said pilot valve, a follow-up connection for said speed responsive means, and hydraulic means for transmitting movement from said one separate device to the follow-up connection.

3. The combination with an elastic fluid

turbine, of a primary valve means controlling the flow of elastic fluid to the turbine, a fluid-actuated motor for moving the valve means, a pilot valve for controlling the fluid pressure supplied to said motor, a second valve means for controlling the flow of fluid at an intermediate point in the turbine a fluid-actuated motor including a pilot valve for moving the second valve means, a unitary structure comprising two movable devices and an operating device adapted to move both said movable devices, means for effecting movement of said operating device in response to an operating condition of the turbine, and hydraulic means for transmitting movement from said movable devices to said pilot valves.

4. The combination with an elastic fluid turbine, of a primary valve means controlling the flow of elastic fluid to the turbine, a fluid-actuated motor for moving the valve means, a pilot valve for controlling the fluid pressure supplied to said motor, a second valve means for controlling the flow of fluid at an intermediate point in the turbine, a fluid-actuated motor including a pilot valve for moving the second valve means, a unitary structure comprising two movable devices and two operating devices, each operating device being adapted to move both said movable devices, means for effecting movements of said operating devices in response to operating conditions of the turbine, and hydraulic means for transmitting movement from said movable devices to said pilot valves.

5. The combination with an elastic fluid turbine, of primary valve means controlling the flow of elastic fluid to the turbine, a fluid-actuated motor for moving the valve means, a pilot valve for controlling the fluid pressure supplied to said motor, a second valve means for controlling the flow of fluid at an intermediate point in the turbine, a fluid-actuated motor including a pilot valve for moving the second valve means, a unitary structure comprising two movable devices and two operating devices, each operating device being adapted to move both said movable devices, a speed governor for effecting movement of one of said operating devices, means for effecting movement of the other of said operating devices in response to another operating condition of the turbine, and hydraulic means for transmitting movement from said movable devices to said pilot valves.

6. The combination with an elastic fluid turbine, of valve means controlling the flow of elastic fluid to the turbine, a fluid-actuated motor for moving the valve means, a pilot valve for said motor, a speed governor, a pilot valve connected to the speed governor, a movable device, an operating device for moving it, an hydraulic operating con-

nection between said movable device and said first-named pilot valve, and fluid pressure means for said operating device controlled by said second-named pilot valve.

- 5 7. The combination with an elastic fluid turbine, of a valve means controlling the flow of elastic fluid to the turbine, a fluid-actuated motor for moving the valve means, a pilot valve for said motor, a speed governor, a pilot valve connected to the speed governor, a movable device, an operating device for moving it, an hydraulic operating connection between said movable device and said first-named pilot valve, fluid pressure 10 means for said operating device controlled by said second-named pilot valve, a follow-up connection for said second-named pilot valve, and hydraulic means connecting the operating device to said follow-up connection.

- 15 8. The combination with an elastic fluid turbine having a valve means controlling the flow of elastic fluid to it and a valve means controlling the flow at an intermediate point in the turbine, of fluid-actuated motors each including a pilot valve for moving said valve means, two movable devices, hydraulic means connecting said movable devices to said pilot valves, two operating devices each 20 adapted to move said movable devices, means controlled by the speed of the turbine for effecting movement of one of said operating devices, and means responsive to another operating condition of the turbine for effecting movement of the other of said operating devices.

- 25 9. The combination with an elastic fluid turbine having a valve means controlling the flow of elastic fluid to it and a valve means controlling the flow at an intermediate point in the turbine, of fluid-actuated motors each including a pilot valve for moving said valve means, two movable devices, hydraulic means connecting said movable devices to said pilot valves, an operating device which moves said movable devices in the same direction, an operating device which moves said movable devices in opposite directions, means controlled by the speed of the turbine for effecting movement of the first-named operating device, and means controlled by another operating condition of the turbine for effecting movement of the second-named operating device.

- 30 10. The combination with an elastic fluid turbine having a conduit connected to an in-

termediate stage, valve means controlling the admission of elastic fluid to the turbine, valve means controlling the flow of elastic fluid at said intermediate stage and fluid-actuated motors including pilot valves for actuating said valve means, of a unitary structure comprising two movable devices, an operating device for moving them in the same direction, and an operating device for moving them in opposite directions, motion-transmitting means connecting said movable devices to said pilot valves, means controlled by the speed of the turbine for effecting movement of the first-named operating device, and means responsive to the pressure in said conduit for effecting movement of said second-named operating device.

35 11. The combination with an elastic fluid turbine having a conduit connected to an intermediate stage, valve means controlling the admission of elastic fluid to the turbine, valve means controlling the flow of elastic fluid at said intermediate stage, and fluid-actuated motors including pilot valves for actuating said valve means, of a unitary structure comprising a lever, a fulcrum for the lever, two movable devices connected to the lever, an operating device for moving the fulcrum of the lever, and an operating device for turning the lever on its fulcrum, motion-transmitting means connecting said movable devices to said pilot valves, means controlled by the speed of the turbine effecting movement of one of said operating devices, and means responsive to the pressure in said conduit for effecting movement of the other of said operating devices.

40 12. The combination with an elastic fluid turbine having valve means controlling the admission of elastic fluid to the turbine and valve means controlling the flow of elastic fluid at an intermediate point in the turbine, of a unitary structure for controlling said valve means comprising two movable devices, a lever to which they are connected, an adjustable fulcrum for the lever, and operating devices for effecting movements of said lever, motion transmitting means whereby said movable devices operate said valve means, and means for effecting movements of said operating devices in response to operating conditions of the turbines.

In witness whereof, I have hereunto set my hand this 21st day of April 1926.

REGINALD G. STANDERWICK.
